UNITED STATES PATENT OFFICE

MICHAEL J. BOYLE, OF CHICAGO, ILLINOIS

VALVE AND METHOD OF MANUFACTURING SAME

Application filed March 19, 1926. Serial No. 95,880.

This invention relates to valves such as used for internal combustion engines and to a method whereby the valve head is forged and fastened onto the stem during the forging operation.

The objects of this invention are to provide an improved valve for internal combustion engines and more particularly automobile engines; to provide a valve having a novel seating portion; to provide a valve in which a predetermined heat may be retained at the upper surface during the operation thereof; to provide a method of manufacturing valves whereby the head will be securely fastened to the stem; to provide a method of forging a valve head and simultaneously welding it to the stem as well as covering a portion of the stem to protect the same; and to provide such other improvements as will be described more fully hereinafter.

In the accompanying drawings illustrating this invention:

Figure 1 is a sectional view showing a stem with a blank or billet in position thereon while being heated by electric current;

Figure 2 is a sectional view showing the first pressing or forming operation;

Figure 3 is a sectional view showing the final forming or forging operation; and

Figure 4 is a view showing the valve in position in the engine.

I provide a cylindrical billet or blank 5, having a hole 6 which preferably extends entirely through the same. This blank may be made of any suitable material for a valve head such as a high chromium alloy or the like. The valve stem 7, which is made of any suitable material for this purpose, such as chrome, nickel, steel or the like, is inserted in the hole 6. The blank and adjacent portion of the stem is then heated in any suitable manner, but preferably by electricity. This is accomplished by inserting the blank between two terminals 8 and 9 as indicated in Figure 1 and allowing the current to pass therethrough until the blank is raised to a forging or welding heat. The stem and blank are then placed in a die 10 as shown in Figure 2 which is mounted in a suitable press, and the stem 7 is held in a guide in

the usual manner. A cooperating die 11 is then pressed downwardly over the blank and the blank is then forged into the form shown in Figure 2. In this first operation, a disk or flange 12 is formed with an annular seat 13 on its lower face. The lower end of the blank, which is tapered or cut away as shown at 19, is also thickened and formed into a tapered sleeve or projection 14 which extends downwardly for some distance below the disk 12. A groove 15 is also formed adjacent to the inner circumference of the seat 13 so that the disk is somewhat thinner at this point than it is at its outer portion.

The stem and blank or partially-formed head while held in the die 10 are then acted upon by a second top die 16 as shown in Figure 3. The stem during these operations is supported in a guide 17 which may be made in any well known manner. The depth of the guide is preferably adjustable for different lengths of stems and to provide an abutment at the bottom for supporting the stem against longitudinal thrust. In order to indicate such adjustability, I have shown a removable plug 18 at the bottom of the guide which may be made of any suitable length for different stems. The coacting die 16 is pressed downwardly against the top of the blank and the stem, and the valve head is then completely forged as shown in Figure 3 and is preferably partly welded to the stem, the upper end of which is also expanded or headed, substantially as shown.

The completed valve has a flange 20 which is preferably of the same diameter as the disk 12 and which is pressed against the disk in the forming operation, so that it lies closely against the same. In other words, these operations provide a head 21 with an inwardly extending joint 22, as the flange and disk are not welded together. The die 16 which engages with the upper end of the stem 7 causes this end to be expanded or riveted with an annular projection 23 which is embedded in the head 21 and in most instances is welded to the head, at least around its outer edge, and for a short distance downwardly. The completed upper surface of the valve will be seen to have a central concave portion 24 with an

outer beveled portion 25. The stem is also slightly bulged as shown at 26, due to the longitudinal pressure and this portion is enclosed in the sleeve or tapered extension 14. 5 This sleeve will not ordinarily be welded to the stem, as the pressure is not sufficient at this point to cause such welding action.

The arrangement of the valve in an engine block 28 is shown in Figure 4, and the stem 10 is positioned in the usual guide 29. In this arrangement, the valve seat 13 engages with a flat seat 30 in the engine. In a construction of this type, the heat of the valve head is apt to be rapidly dissipated or transferred 15 on coming in contact with the surface of the engine block which is usually cooled, either by water or other liquid, as shown, or by air. It is however desirable to have the upper surface of the valve kept sufficiently hot so as to 20 prevent the accumulation of carbon thereon, as such carbon is apt to accumulate if the valve is cooled below a certain temperature.

In my copending application for valves and valve manufacture, I have shown a valve 25 having a substantially solid head and one which is particularly adapted for exhaust valves, as the cooling action just referred to tends to keep the valve cooled to the proper temperature. However, if such valve is used 30 as an intake valve, it may, in some cases, run too cool and be subject to the accumulation of carbon. The present valve is constructed so that it is not apt to cool as rapidly as a valve having a substantially solid head or as 35 shown in such copending application, and it is therefore especially adapted for use as an intake valve. It is well known that heat will not pass through a crack or joint or even a welded area as rapidly as through solid metal, therefore the crack or joint 22 between the flange 20 and the disk 21 will tend to stop the heat passing from the upper surface of the valve down through the seat, and therefore, a larger amount of heat will be retained 40 on the upper surface, and it also prevents the cooling of the upper surface by the incoming gas when the valve is used on the intake. The upper end of the stem also becomes heated, but as this heated area is relatively small, 45 it will remain sufficiently hot to prevent the accumulation of carbon on the exposed portion thereof. The double disk or double flanged head will also tend to prevent undue noise when the valve seats, and this arrangement will also tend to provide a certain amount of flexibility for the engaging portion of the valve, thus aiding quiet operation and also positive seating of the valve, and also prevents wearing of the valve seat. The peculiar shape of the valve is such that it tends 55 to prevent warping of the head and as the upper portion of the stem is protected by the sleeve 14, the hot gases will not come in engagement with the stem as they pass out under the valve when the valve is used for the 60

exhaust but will be deflected downwardly toward the port, as will be readily seen from Figure 4.

My improved valve may be made in various sizes and forms for different conditions and in the following claims I do not wish to be limited to the exact construction or method herein described, but what I claim and desire to secure by Letters Patent is:

1. The method of manufacturing valves which consists in inserting a valve stem in a blank, then heating the blank and the adjacent portion of the stem, then subjecting the blank and stem to a forging action whereby a disk will be formed on the blank, and then subjecting the parts to a second forging action whereby a flange will be formed which engages with said disk and lies over the same and the end of the stem will be enlarged and secured in the head. 75

2. The process of making valves which consists in placing a cylindrical blank on a stem or rod, then heating the blank and adjacent portion of the stem, then forging a disk which projects outwardly from the central portion of the blank and then expanding the upper portion of the blank and stem whereby the valve head will be completed with a disk or annular portion overlying the first named disk. 90

3. The method of valve manufacture which consists in providing a cylindrical blank having an axial hole therethrough and having one end reduced, then inserting a stem in said hole with one end flush with the end of the blank, then heating the blank by electricity, then placing the blank and stem in a die and pressing a disk outwardly from the blank, with a seat on the lower face thereof, and then pressing the parts by another die and expanding the upper portion of the blank outwardly over the disk and enlarging the end of the stem which is embedded in the blank and forming a sleeve which projects downwardly below the disk and engages with the stem. 100

4. A method consisting in placing a blank on a stem and heating the same, then forming a relatively thin web or disk which projects outwardly from approximately the center of the blank and finally pressing the end of the blank and stem to form a relatively heavy disk which overlies the first named disk. 115

5. The method of forming valves which consists in subjecting a blank to a forging action to form an outwardly projecting disk around the same and then subjecting the blank to a second forging action to complete the valve head and to form a second disk-like portion which overlies the first disk and engages therewith. 120

6. A valve comprising a stem having an enlarged end, and a head formed of a single piece of metal fitting over said end and hav- 130

ing its outer periphery in the form of outwardly projecting overlapping leaves.

7. A valve comprising a stem with a head formed of a single piece of metal forged and welded thereon, the end of the stem being enlarged and fitting in a corresponding recess in the head, the head having an outwardly extending lower disk with a seat thereon and having an outwardly extending upper disk which contacts with the lower disk.

8. A valve head having an annular flange with a seat thereon, and an upper outwardly projecting flange which contacts with the first named flange, and which is formed integrally therewith.

9. The combination of a stem having a valve head formed of a billet and forged thereon, said head having a lower outwardly projecting annular web and having an upper integrally formed web or flange and also having a downwardly projecting sleeve for covering the adjacent portion of the stem.

10. A poppet valve having a head formed from a single billet and provided with a laminated integrally formed periphery.

11. A poppet valve comprising a stem with a head formed of a single piece of metal with laminated edges and having a projection enclosing the adjacent portions of the stem.

12. A valve head formed of a single piece of metal having its outer periphery made in the form of a plurality of overlapping portions fitting closely together.
